International Search Report and Written Opinion dated Jun. 4, 2021 issued in PCT Application No. PCT/US21/23686.

Primary Examiner — Austin Murphy*(74) Attorney, Agent, or Firm* — Troutman Pepper Hamilton Sanders LLP; Christopher C. Close, Jr.; Brandon M. Reed(57) **CLAIM**

The ornamental design for a handheld steam iron, as shown and described.

DESCRIPTION

FIG. 1 is a perspective view of our new design for a handheld steam iron shown in the open configuration;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The broken lines illustrate portions of the handheld steam iron that form no part of the claimed design.
